UNITED STATES PATENT OFFICE

ELMER J. BURT, OF OAKLAND, CALIFORNIA, ASSIGNOR TO THERMOSTOVE CORPORATION,
LTD., OF RENO, NEVADA, A CORPORATION OF NEVADA

THERMOSTAT SWITCH

Application filed January 28, 1929, Serial No. 335,403. Renewed May 22, 1931.

This invention relates to electric switches and particularly to one for use in connection with electric thermostoves, in which it is desired to discontinue the operation of the electric heating element after the food being cooked has reached the boiling temperature and is throwing off steam.

The principal object of my invention is to provide a switch for this purpose which is operated by steam heat in such a manner that the circuit will be opened when such heat has been attained in a positive and automatic manner. The switch arrangement also is such that it may be either closed or opened at will, independently of the automatic switch opening structure but incapable of functioning to close the switch until the heat in the stove has dropped to at least below the boiling point.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved switch showing the contacts closed.

Fig. 2 is a similar view with the contacts open.

Fig. 3 is a top plan view of the steam passage unit of the switch partly in section and showing the same mounted in connection with the stove.

Fig. 4 is a perspective view of a pawl member, detached.

Referring now more particularly to the characters of reference on the drawings, the numeral 1 denotes a box or casing of porcelain or similar insulating material adapted to be disposed on the side of the stove on the outside thereof. The box is held in this position by a threaded stem 2 projecting through the back of the box at one end and through the double walls 3 of the stove, to which walls

50 the stem is clamped by suitable nuts 4. A

block 5 is secured to the inner end of the stem inside the box, to which block is secured an aluminum pipe 6 which extends horizontally to the opposite end of the box and is freely open to the atmosphere at such end.

The stem has a passage 7 from its end inside the stove to a termination inside the block and communicating at such end with the adjacent end of the pipe 6 as shown in Fig. 3.

Mounted in the box is a fixed contact 8 to which is connected a wire 9 leading to one terminal of the stove heating element (not shown). Positioned above the contact 8 to cooperate therewith is another contact 10 which is connected to one end of a horizontally extending flat spring arm 11 which is pivoted intermediate its ends onto the back wall of the box. A spring 12 acts on the arm to normally hold the contacts separated. The contact 10 is connected to a flexible wire 13 leading to a connection with a plug stem 14 projecting outwardly from the end of the box; the corresponding stem 15 being connected by a wire 16 to the other terminal of the element.

Pivoted in the box toward the end thereof opposite the contacts and positioned to project under the adjacent end of the arm 11 is a vertical pawl 17, which when under the arm depresses the opposite end of the same against the action of the spring 12 so that the contacts will firmly engage each other to close the circuit. A spring 18 associated with the pawl tends to turn the same toward an engaging position with the arm. Formed as a part of the pawl in offset relation to the pivot thereof and in the direction of the contacts is a transversely projecting extension 19 which passes over a flat strip 20 of bimetal which extends along and normally rests on the pipe 6. This strip is free at its extension engaged end but is permanently secured at its opposite end on the block 5. This bimetal strip is so disposed that its expandible portion is underneath, so that when affected by heat it will curl upwardly at its free end.

By means of this construction therefore it will be seen that when steam is generated

100

in the cooker and is passing through the steam and pipe heating the same, the heat will be transmitted to the bimetal strip, causing the latter to assume the above named warped position. If the pawl has been previously turned so as to be engaged with the arm 11 and the switch is therefore closed, the extension 19 will be depressed and will bear firmly on the bimetal strip. As the latter warps up, it raises the extension, causing the pawl to be thrown clear of the arm 11 against the resistance of the spring 18, the strength of said spring being insufficient to resist the warping movement of the bimetal strip. The spring 12 then acts on the arm 11 to raise the contact 10 clear of the contact 8, opening the switch. The switch will not then again close, even with the return of the strip to its normal position, on account of the fact that the released end of the arm 11 then drops in front of the pawl, preventing the latter from moving under the arm with the pressure of the spring 18.

The switch can only be reset or reclosed by hand, when the bimetal strip has cooled off. This is done by means of a vertical finger actuated stem 21 mounted in the top of the box 1 and engaging the arm 11 between the pivot and contact. A forceful depression of this stem therefore first causes the contacts to be engaged and then causes the pawl end of the arm to be raised (owing to the spring construction of the arm) so that the pawl is free to pass under the same. If the bimetal strip is still in a heated and warped condition, the pawl cannot move under the arm, but if said strip has cooled off the force of the spring 18 will then cause the pawl to move under the arm and hold the same in a contact closing position. This arrangement therefore, as will be evident, prevents the closing of the switch when heat conditions in the cooker are such that a further generation of heat would be damaging to the food being cooked.

The switch however may be opened at any time by another vertical finger actuated stem 22 mounted in the bottom of the box and engaging the extension 19 between the pipe 6 and the back of the box, so as to raise said extension and thereby move the pawl clear of the arm 11 regardless of the setting of the strip 20.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what

I claim as new and useful and desire to secure by Letters Patent is:

1. A thermostat switch including a tubular member adapted to receive steam there-through, a bimetal strip positioned to be affected by the heat of said member and fixed against movement only at one end, whereby said strip when heated can warp out of its normal plane at the opposite end, cooperating contacts, an arm pivoted intermediate its ends in a fixed position relative to the strip and on one end of which one of the contacts is mounted, spring means acting on the arm to hold the contacts separated, a pivoted pawl whose outer end is adapted to pass under the end of the arm opposite to the contact to then maintain the contacts engaged against the resistance of the spring, and an extension formed with the pawl and engaged by the free end of the bimetal strip, said extension being positioned so that when moved by the warping of the strip the pawl will be withdrawn from under the arm.

2. A device as in claim 1, with spring means acting on the pawl to move the same to an arm-engaging position and of a strength such as to be overcome by the warping of the strip, the end of the arm, when released from the pawl, projecting in front of and below the outer end of the pawl.

3. A device as in claim 1, with spring means acting on the pawl to move the same to an arm-engaging position and of a strength such as to be overcome by the warping of the strip, the end of the arm when released from the pawl projecting in front of and below the outer end of the pawl, and a finger-pressed member associated with the arm and engaging the same in a position to cause the said end of the arm to be raised above the outer end of the pawl.

4. A device as in claim 1, in which the arm is of flexible material, with a finger-pressed stem bearing down on the arm between its pivot and the contact whereby to cause the pawl engaged end of the arm to be raised to permit the pawl to pass under the same.

In testimony whereof I affix my signature.

ELMER J. BURT.
